WILLIAM H. LAUBACH, OF PHILADELPHIA, PENNSYLVANIA

Letters Patent No. 77,387, dated April 28, 1868.

IMPROVEMENT IN VALVES FOR GAS-ENGINES.

The Schedule referred to in these Letters Patent and making part of the same.

TO ALL WHOM IT MAY CONCERN:

Be it known that I, WILLIAM H. LAUBACH, of Philadelphia, in the State of Pennsylvania, have invented a new and useful Improvement in Gas-Engines; and I do hereby declare that the following is a full, clear, and exact description of the same, reference being had to the accompanying drawings, and letters of reference marked thereon, making a part of this specification, in which—

Figure 1 is a side elevation.

Figure 2, a transverse vertical central section through the line $x-x$, fig. 1.

Figure 3, side elevation of the slide-valve and valve-seat in use in my machine.

Figure 4, a detached plan view of the sleeve m and one of the cams k .

To enable those skilled in the art to make and use my invention, I now proceed to describe its construction and operation.

Similar letters in the drawings refer to like parts.

This invention belongs to that class of engines in which the motor is air expanded in the cylinder by the combustion of some inflammable gas, which combustion is brought about by the agency of electricity.

The invention consists of an arrangement of devices for regulating the flow into the cylinder of air alternately with a mixture of air and gas, in such manner that the mixture shall always be in due proportion, that is to say, about in the proportions of nine parts of air and one part of gas, and that the flow of the mixture shall always continue until the combustion takes place, as will hereinafter more fully appear.

A represents an ordinary engine-cylinder, provided with the usual induction and eduction-ports, the latter of which are not shown. The former is shown at a , the valve-seat being provided with two openings, a' a'' . The valve a is of the common slide species, and held in place by the brackets b b fastened by screws.

An orifice, c , of similar shape with the openings a' a'' , is made at the centre of the valve a . Between the brackets b is fastened a cap, c' , which, being hollow, forms a chamber, c'' , between itself and the valve a .

A circular valve-support, d , projects from the outer side of the cap c' , in which works the disk-valve d' , fitted tightly to the inner surface of its support d .

The bottom of the valve-support d is closed, with the exception of a circular opening, in which may be fitted a ring, d'' , projecting some little distance below the bottom of the support, within which ring enters a projection, e , of prismatical or other convenient shape, from the bottom of the disk-valve d' , for the purpose of guiding the same during its upward and downward movements. A ring, e' , placed upon the top of the valve-support d , has a flange, e'' , projecting downward from its inner edge, which flange is provided with a screw-thread corresponding with a screw-thread on the upper part of the inner surface of the valve-support d , by means of which screw-threads the flange e'' may be adjusted at any desired position on the support d .

An arm, h , is secured to one side of the support d , and, extending upward, is bent inward at the proper height, and to a sufficient extent to form a guide for the upper end of the stem d''' of the valve d' , which stem is bent to one side, as shown at h' , far enough to afford space for the rotation of the cams k k of the horizontal shaft e . A sharp tooth, k' , is formed on the stem d' , on the side opposite the said curved portion, for use in connection with the cams k .

The cams k are of wedge-shape, one side of each being parallel with the axis of the shaft l , and the other side being inclined thereto.

The cams k are affixed to a sleeve, m , sliding on the shaft l : the latter being square in cross-section for a portion of its length, so as to insure the rotation of the sleeve m with the shaft l .

The sliding of the sleeve m is effected by a lever, n , pivoted to the bent arm h above the shaft l , and bifurcated at its lower end, as shown at n' n'' ; said bifurcations clasping a flange, m' , on the end of the sleeve m .

Rotation is communicated to the shaft l by any suitable means; it being necessary that said shaft l should revolve as often as the main shaft does; provided two cams k are employed, and at the rate of two revolutions for every one of the main shaft, if one cam k is employed.

The gas used to discharge the before-mentioned function enters the machine at the orifice d'' in the bottom

of the valve-support d , and proceeds thence into the chamber e'' . The air employed in connection with the gas enters at the upper orifice of the support d , above the disk-valve d' . A piece of wire gauze, o , is stretched across the mouth of the chamber e'' , near the valve d' , to effect the more perfect mixing of the currents of gas and air. A partition of buck-shot may be used instead of gauze, if desired.

The disk-valve d' controls the flow of the gas into the machine. While resting on its lower seat, it completely closes the orifice d'' , so that no gas can enter. It is raised from its lower seat by one of the cams k .

The bevelled sides of these cams are inclined upward and inward, by which means, when such inclined sides come in contact, during the revolution of the shaft, with the inner curved side of the tooth k' , the latter slips easily over the former, and the stem d''' , with the valve d' , is raised off its lower seat, admitting the gas. The valve d' remains elevated until the cam k passes the tooth k' . The straight sides of the cams k are perpendicular, so that the moment the upper surface of the cam passes from under the tooth k' the valve-stem d''' and valve d' fall and close the orifice d'' , shutting off the gas.

The length of time during which the valve d remains elevated, as well as the point of time when such elevation begins, are governed by the position of the sleeve m on the shaft l . In proportion as the tooth k' passes over a narrower or wider part of the cam k , and comes in contact with a point nearer to or farther from the wide end of said cam, the said tooth remains elevated a longer or shorter time, and such elevation begins sooner or later.

As regards the current of air passing into the machine, it is evident that its volume is controlled by the position of the flange e'' with respect to the valve d . By means of the before-mentioned screw-threads, the flange e'' can be adjusted at any desired height above said flange. I propose to station it at such a height, that the volume of air passing into the machine shall be about in the proportion of nine to one with respect to the volume of gas, which proportion I consider productive of the highest degree of force extractible from any compound of these elements. This proportion remains always the same, whether the flow of gas continues for a longer or shorter period.

The communication between the chamber e'' and the upper orifice of the valve-support is always to be kept open, so as to insure free admission of air at all times to the latter.

To set my engine in motion, supposing the piston to be at one end of the cylinder, it is, in the first place, to be drawn towards the centre by hand through the agency of the fly-wheel. The slide-valve a is so arranged as to admit a supply of air into the cylinder, behind the piston, from the beginning of the stroke. At the commencement of the stroke, the sleeve m should be so placed as not to bring the cam k into operation, and thus admit gas until after the piston has passed beyond an eighth stroke, more or less. The slide-valve a completes its forward throw simultaneously with the completion of a quarter stroke by the piston, and at once commands its return throw, which it completes by the time the piston finishes its half stroke. The valve d rises at any desired point of the stroke, and admits gas, which, passing through the gauze o , is mixed with air in the chamber e' , from which a current of the intermingled vapor enters the cylinder until the slide-valve closes the orifice a' or a'' .

An electric battery, at this moment, by means of a suitable mechanism, not here described, causes the ignition of the gas, the wire which communicates the spark ending in the passages a' a'' , where the gas is certain to be, by reason of its entering at that point at the instant of the advent of the electric influence, the flow of the combined currents of gas and air being always synchronous with the last part of return throw of the slide-valve.

The commencement of such flow may be made simultaneous with that of the forward throw of the slide-valve, if desired, thus admitting a combined current of gas and air from the very beginning of the stroke of the piston, simply by setting the sleeve m in such position on the shaft l that the widest parts of the cams k are brought into contact with the tooth k' .

The combustion of the gas takes place, as before described, when the piston has completed a half stroke, which combustion expands the air in the cylinder at the time, by the force of which expansion the stroke is completed.

It is necessary to the proper operation of my engine that air alone should enter the cylinder at the beginning of the stroke, in order that the carbonic-acid gas resulting from former combustions, and remaining in the cylinder, may be duly disposed of.

The point at which the commingled current of gas and air enters the cylinder is controlled by the governor of the engine, which is suitably connected with the sleeve m .

Having thus described my invention, what I claim as new, and desire to secure by Letters Patent, is—

The devices herein described, consisting of the sliding sleeve m , provided with the cams k , constructed as described, the lever n , shaft l , valve d' , and stem d''' , with its tooth k' , for regulating the flow of a combined current of gas and air, alternately with air alone, into the cylinder of a gas-engine, in such a manner that the former current shall continue to flow until the closing of the induction-port and the moment of the ignition of said gas, substantially as described.

W. H. LAUBACH.
